TOY ROBOT

Leslie Perhacs, Jr., Topanga, Calif., assignor to Cragstan
Industries, Inc., New York, N.Y., a corporation of New
York

Filed Mar. 12, 1969, Ser. No. 16,218

Term of patent 14 years

Int. Cl. D21—02

U.S. Cl. D34—15

FIG. 1

FIG. 3

FIG. 2

FIG. 4

FIG. 5

FIG. 1 is a perspective view of my new design for a toy robot;

FIG. 2 is a side elevational view of the side opposite that shown in FIG. 1;

FIG. 3 is a top plan view taken along the line 3—3 of FIG. 2;

FIG. 4 is a rear elevational view taken along the line 4—4 of FIG. 2; and

FIG. 5 is a bottom plan view taken along the line 5—5 of FIG. 2.

I claim:

The ornamental design for a toy robot, as shown.
